Inventor;
Henry T. Sisson

UNITED STATES PATENT OFFICE.

HENRY T. SISSON, OF PROVIDENCE, RHODE ISLAND.

PORTFOLIO.

Specification forming part of Letters Patent No. 23,506, dated April 5, 1859; Reissued March 13, 1866, No. 2,199.

To all whom it may concern:

Be it known that I, HENRY T. SISSON, of the city of Providence, in the county of Providence and State of Rhode Island, have 5 invented a new and useful Improvement in Portfolios and Paper-Files; and I do hereby declare that the following is a full, clear, and exact description of the same, reference being had to the accompanying drawing, 10 forming part of this specification, in which—

Figure 1, is an inside view of an open portfolio with my improvement. Fig. 2, is a central longitudinal section of what I term the barrel which forms the back of the portfolio. Figs. 3 and 4 are transverse sections of the portfolio near the middle of its 15 length. Figs. 5 and 6 are transverse sections of the same near one end but in different planes.

20 Similar letters of reference indicate corresponding parts in the several figures.

My invention consists in a novel apparatus which may be applied in the back of a portfolio or attached to a suitable handle for 25 the purpose of holding and securing music sheets, pamphlets or papers of any kind.

To enable others to make and use my invention I will proceed to describe it.

A, is what I term the "barrel" consisting 30 of a tube of metal, wood, or other material somewhat longer than the papers which are intended to be held, said tube being left entire for some distance, say from half an inch to one inch, from each end, and having 35 nearly one half the intervening portion cut away in a plane parallel with its axis, having an opening *a*, *a*, of a length equal to or somewhat greater than the length of the papers. To one side of this barrel there are 40 permanently attached two or more pointed hooks or teeth *b*, *b*, curved in a form to correspond with the arch of the barrel and extending nearly across the opening *a*, *a*, as shown in Figs. 3 and 4.

45 B, is what I term the shaft arranged within the barrel, extending from end to end thereof, and projecting slightly from one end thereof. The terminal portions of the shaft are cylindrical and fitted into the complete 50 tubular terminal portions of the barrel so as to turn freely therein; but the part of the said shaft which enters the open part *a*, *a*, of the barrel, is half cut away or has a cavity formed in it corresponding with the

opening *a*, *a*, and one edge of this part is 55 formed to project beyond the interior of the cavity *a*, *a*, so that it may lap over either side thereof as shown at *c*, *c*, in Figs. 3 and 4, and in this lapping part *c*, *c*, there are openings *d*, *d*, (see Fig. 1) to permit it to 60 pass the hooks or teeth *b*, *b*. In the flat portion of the shaft there is formed a recess whose back *e* (see Figs. 3 and 4) constitutes a gage for the edges of the sheets.

The marginal portion of that side of the 65 cavity over which the flat side of the portion *c*, *c*, of the shaft laps and to which the hooks or teeth *b*, *b*, are attached, is made flat to correspond with the shaft and the marginal portion of the other side of the cavity 70 beveled to correspond with the rounded side of the shaft. Provision is made for inserting the shaft in the barrel by making a portion of one of the complete tubular portions of the barrel movable, and when inserted the 75 shaft is secured by replacing and securing the movable portion of the barrel.

g, *g*, (Figs. 2 and 6) are coiled springs applied in suitable cavities formed between the complete tubular terminal portions of 80 the barrel and the portions of the shaft which fit thereto, and having each one end attached to the shaft and the other to the barrel and operating to turn the shaft in a direction to press the lap *c*, *c*, toward the 85 flat side of the cavity *a*, *a*, as shown in Fig. 4. *f*, is a spring latch attached to the interior of the barrel within one of its complete tubular portions, and *g*, is a stop formed on the shaft to engage with said latch and hold 90 the shaft whenever the latter has been turned to the position shown in Fig. 3. The spring of the latch *f*, has attached a button *i*, which protrudes through to the exterior of the barrel for the purpose of applying the pressure 95 of the thumb or finger for liberating the stop *g*, from the latch and leaving the shaft under the influence of the springs *d*, *d*.

The shaft has attached to the end which projects from the barrel a finger piece or 100 head *m*, which may be taken hold of to turn it, and this head is all that needs to project from the ends of the portfolio. The boards C, C, of the portfolio are simply attached by cloth or leather to that side of the 105 barrel B, which is left entire, by means of a back *j*, of cloth, leather or other substance, and straps *k*, *k*, may also be applied to con-

nect the interiors of the boards with the opposite or inner halves of the complete tubular terminal portions of the tube.

To place music or other sheets in the portfolio, it should be laid open and the shaft B, turned in the barrel A, till the stop g, catches the latch f, as shown in Fig. 5, which brings the recessed face portion of the shaft to the position shown in Fig. 3. The sheets 10 are then held loosely in the hand with the edges which are to be secured under the points of the hooks or teeth b, b, and close against the gage e, as shown by the red lines in Figs. 1 and 3, which represent them, and 15 on the button i, being depressed to liberate the stop g, from the latch f, the springs d, d, carry the shaft rapidly to the position shown in Fig. 4, driving the sheets on to the hooks or teeth and down to the heels 20 thereof and throwing them over to the position indicated by the red lines in Fig. 4, leaving them clamped between the lap of the shaft and the flat face or edge of the barrel. In case of the springs not being strong

enough to force the sheets over the hooks or 25 teeth, the shaft may be turned by taking hold of the head m, and the springs will not fail to hold it when turned.

By the simple omission of the boards C, from the barrel A, the same contrivances 30 which I have described for holding sheets in a portfolio, constitute a file for holding newspapers or other sheets, but for the file I should prefer to substitute a handle for the simple finger piece or head m. 35

Having thus described my invention, what I claim as new and desire to secure by Letters Patent, is—

The combination of the barrel A, shaft D, hooks or teeth b, b, a spring or springs d, d, 40 spring latch f, and stop g, the whole constructed and arranged substantially as and for the purposes herein set forth.

HENRY T. SISSON.
